(57) **CLAIM**

The ornamental design for a casing for electrostimulator with light emitting device, as shown.

DESCRIPTION

FIG. 1 is a side perspective view of the casing for electrostimulator with light emitting device;

FIG. 2 is a top plan view of the casing for electrostimulator with light emitting device;

FIG. 3 is a bottom plan view of the casing for electrostimulator with light emitting device;

FIG. 4 is a right side plan view of the casing for electrostimulator with light emitting device;

FIG. 5 is a left side plan view of the casing for electrostimulator with light emitting device;

FIG. 6 is a front plan view of the casing for electrostimulator with light emitting device; and,

FIG. 7 is a rear plan view of the casing for electrostimulator with light emitting device.

The broken lines in FIGS. 3 and 7 are included for the purpose of illustrating a portion of the casing for electrostimulator with light emitting device that forms no part of the claimed design.
